TOY VEHICLE APPARATUS

Filed Feb. 25, 1931

Inventor

James Francis Key

By

Yours truly,

Attorneys.

UNITED STATES PATENT OFFICE

JAMES FRANCIS KEY, OF PASADENA, CALIFORNIA, ASSIGNOR OF SIXTY-EIGHT
PER CENT TO JAMES IRVINE, JR.

TOY VEHICLE APPARATUS

Application filed February 25, 1931. Serial No. 518,101.

This invention relates to a toy vehicle apparatus and refers particularly to an electric driven toy vehicle and means for guiding the electric vehicle capable of operation without 5 the usual tracks.

Heretofore electric toy vehicles have either 10 operated upon tracks or have merely revolved around a central post. It is the general object of the present invention to provide a toy vehicle which can be run on the ground or floor through a variable path and to provide 15 the toy vehicle with means for connecting electric wires thereto and for automatically supporting and playing in and out electrical wires as the operations of the vehicle require.

More particularly, it is the object of the 20 present invention to provide an electric vehicle which may be guided by a string or cable looped around a plurality of supports, in which the electrical vehicle is provided 25 with a swivel contact connecting the vehicle with electric lead lines and in which the electric lead lines are provided with a simple 30 and effective supporting means capable of holding the lead lines above the ground or surface of operation where they are out of 35 possible contact with the vehicle, together with means for automatically paying out the 40 line as is required in the different motions of the vehicle.

Another object of the present invention is 45 to provide a construction of a toy vehicle and operating accessories therefor for connecting electric lines thereto, which operating accessories may be readily detached from the 50 toy vehicle so that any number of similar or somewhat similar vehicles may, when desired be alternately actuated and controlled by the same appliances.

The present invention, together with 55 various objects and advantages thereof will best be understood from a description of a preferred form or example of a vehicle embodying the invention. For this purpose I

have hereinafter described, with reference to the accompanying drawing, a preferred form or example of the invention, in which drawing

Figure 1 is a diagrammatic view of the 50 invention;

Figure 2 is an enlarged elevation mainly 55 in section showing the detachable electric swivel contact which is used for connecting the electric lines to the toy vehicle;

Figure 3 is a plan view or section on the line 3—3 of Figure 2;

Figure 4 is an enlarged elevation of a 60 hanger used for supporting the lead lines to the toy vehicle;

Figure 5 is a plan view of the hanger;

Figure 6 is an enlarged plan view partially 65 in section of a pulley and bracket used on the vehicle for guiding the vehicle from a string or cable; and

Figure 7 refers to a slightly modified form 70 of supporting means for the electric lead lines.

There is illustrated in the drawing an electrically driven toy vehicle 2 which may be 75 of any usual or preferred form, preferably being of the type which is provided with front wheels 3 for guiding the vehicle and with rear wheels 4. The vehicle may, for example, comprise a front axle 5 carrying 80 steering knuckles connected with rods 6 which rods 6 are pivotally joined to a common front bumper rod 7.

Means are provided for normally urging 85 the front wheels 3 of the vehicle to turn in one direction, i. e. to rotate counter-clockwise as viewed in Figure 1 and one form of said means may provide a coil spring 81, the pivotal connection between the bars 6 and the bumper rod 7.

Attached to the bumper rod 7 is provided 90 a bracket 8, best illustrated in Figure 6, which carries a pulley 9 disposed on a vertical axis and adapted to engage a guiding string or cable 10. The bracket 8 also is pre-

erably provided with a retaining member 11 in the form of a bent wire which will hold the cable or string 10 in contact with the groove of the pulley 9 in operation of the toy 5 vehicle.

The cable or string 10 in operation may be an endless cable or string of any desired length and in operation is merely laid on the floor or ground around one or more posts or 10 like supports 12.

In operation of the vehicle, when the vehicle is driven forward under the power of its electrical motor, the springs 8¹ tend to turn the toy vehicle outwardly away from 15 the guiding cable 10 and the pulley 9 engaging the cable 10 thereby guides the toy vehicle around the post 12 or other objects around which the cable or string 10 is placed.

For connecting electricity to the vehicle 20 for operating the electric motor thereof, the vehicle is preferably provided with a vertical post 13 which is in electrical contact with the frame or ground of the vehicle. Within the hollow post 13 there is provided 25 a rod 14 insulated from the frame by insulations 15 and 16 connected at its lower end as indicated at 17 with a line leading to the motor of the vehicle. It is understood that the motor (not shown) of the vehicle has 30 one end connected with the point 17 and the other end grounded. The upper end of the rod 14 is provided with a knob 18.

19 indicates an electric line carrying two wires covered by a single outer wrapping, 35 which line 19 has a positive and negative wire insulated from each other, the positive wire being connected to the clip 20 and the negative wire to the clip 21. Clips 20 and 21 are mounted by a swivel contact 40 member 22 which comprise the lower U-shaped piece 23 which has an opening 24 of a size sufficient to fit over the post 13 and pivot the member 22 thereon. The member 22 also includes a top member 25 connected 45 with the U-shaped member 23 by bolts 26 and separated therefrom by insulation 27. The top member 25 is provided with a hook-shaped opening 28 adapted to fit under the knob 18 on the rod 14 and provides a sec- 50 ond pivotal point support for the member 22.

Preferably, there is provided a coil spring 29, the lower end of which is supported by the rod 13, as indicated at 30, the upper end of which engages the member 22 to hold the 55 same firmly in position on the rod 13. By this construction the wire connected with the clip 20 is connected with the central rod 14 and the wire connected with the clip 21 is connected through the spring 29 with the 60 outer tubular post 13.

With the construction thus described the line 19 and the swivel contacting member 22 may be readily separated from the post 13 from the toy 2 merely by unlocking the top 65 member 25 of the swivel contact 22 by first

depressing the spring 29, and connection may then be made with any other toy vehicle having a like post.

In order to maintain the line 19 supported in operation so that the toy vehicle 2 will not run into the same or the line become tangled, the vehicle is provided with a hanger 31 consisting of a T-shaped member 32 with a padded contact 33 at one end and a transverse member 34 having hooks 35 at its ends. The top of the T-shaped member 32 extends outwardly and provides a support for the swivel hook 36 of a pulley 37. The supporting member 31 thus described may in operation be readily supported, for example, by the 75 molding 38 in the room.

The pulley 37 in operation may carry the line 19 and to maintain the line slightly taut so that it will be held in the air in operation of the vehicle, a weight 39 is tied on the line 19. Figure 7 illustrates a slightly modified method of utilizing a hanger and pulley, in which case the line 19 in place of being trained over the pulley 37, is attached to a string 20, the other end of which carries a weight 21 and the string 20 is trained around the pulley 37.

While the particular form of toy vehicle herein described is well adapted to carry out the objects of the present invention, it is to be understood that various modifications and changes may be made without departing from the present invention, and this invention includes all such modifications and changes as come within the scope of the following claims.

I claim:

1. A toy vehicle having a contact post comprising an outer tubular member and an inner member, one of said members being grounded to the frame of the vehicle and the other having a lead line which may be attached to the motor of the vehicle, a swivel contact having one member engaging the outer tube and the other member swivelly 105 engaging the inner rod, and means for connecting electric lead lines separately to said members of said swivel contact.

2. A toy vehicle having a contact post comprising an outer tubular member and an inner member, one of said members being grounded to the frame of the vehicle and the other having a lead line which may be attached to the motor of the vehicle, a swivel contact having one member engaging the outer tube and the other member swivelly 110 engaging the inner rod, means for connecting electric lead lines separately to said members of said swivel contact, and spring means 115 engaging said swivel contact member.

3. In a toy apparatus, the combination with an electrically driven toy vehicle having a vertically extending post and an electric contact member swivelly mounted upon said post, a lead line connected with said con- 120

tact member and a pulley carrying hanger around which said line is trained, said hanger having hooked ends by which it may be suspended from a molding, and a weight for normally placing the line from the pulley to the toy vehicle under tension.

Signed at Los Angeles, California, this 19th day of February, 1931.

10 JAMES FRANCIS KEY.
